DISSOLUTION OF LANTHANUM FLUORIDE
PRECIPITATES

Bernard A. Fries, El Cerrito, Calif., assignor to the United States of America as represented by the United States Atomic Energy Commission

Application March 7, 1946, Serial No. 652,829

2 Claims. (Cl. 23—14.5)

This invention relates to a procedure for processing materials containing the element of atomic number 94, known as plutonium, for separating the plutonium from extraneous matter such as substances of the kind present in neutron irradiated uranium as exemplified by uranium and especially fission products, and the like radioactive contaminants. More particularly, this invention concerns a separatory and concentration procedure involving the use of a fluoride type of carrier wherein certain improved procedure is employed in treating the carrier.

As described herein, the isotope of element 94 having a mass of 239 is referred to as 94^{239} and is also called plutonium, symbol Pu. In addition, the isotope of element 93 having a mass of 239 is referred to as 93^{239} . Reference herein to any of the elements or to the term plutonium values is to be understood as denoting the element generically, whether in its free state or in the form of a compound, unless indicated otherwise by the context.

Elements 93 and 94 may be obtained from uranium by various processes which do not form a part of the present invention including irradiation of uranium with neutrons from any suitable neutron source, but preferably the neutrons used are obtained from a chain reaction of neutrons with uranium.

Naturally occurring uranium contains a major portion of $_{92}\text{U}^{238}$, a minor portion of $_{92}\text{U}^{235}$, and small amounts of other substances such as UX_1 and UX_2 . When a mass of such uranium is subjected to neutron irradiation, particularly with neutrons of resonance or thermal energies, $_{92}\text{U}^{238}$ by capture of a neutron becomes $_{92}\text{U}^{239}$ which has a half life of about 23 minutes and by beta decay becomes 93^{239} . The 93^{239} has a half life of about 2.3 days and by beta decay becomes 94^{239} . Thus, neutron irradiated uranium contains both 93^{239} and 94^{239} but by storing such irradiated uranium for a suitable period of time, the 93^{239} is converted almost entirely to 94^{239} .

In addition to the above-mentioned reaction, the reaction of neutrons with fissionable nuclei such as the nucleus of $_{92}\text{U}^{235}$ results in the production of a large number of radioactive fission products. As it is undesirable to produce a large concentration of these fission products which must, in view of their high radioactivity, be separated from the 94^{239} and further as the weight of radioactive fission products present in neutron irradiated uranium is proportional to the amounts of 93^{239} and 94^{239} formed therein, it is preferable to discontinue the irradiation of the uranium by neutrons when the combined amount of 93^{239} and 94^{239} is equal to approximately 0.02 percent by weight of the uranium mass. At this concentration of these substances, the concentration of fission elements which must be removed is approximately the same percentage.

A number of processes have already been proposed for accomplishing the separation and concentration of Pu. Certain of these processes are generically known as the "bismuth phosphate" type process and the "wet fluo-

ride" type of process. These processes are the invention of others and the details of the processes are described in copending applications as for example application Ser. No. 519,714, now U.S. Patent No. 2,785,951, issued March 19, 1957, to be referred to hereinafter, which gives details relative to the aforementioned processes. Consequently, all of the details of operation of the aforementioned processes are not described herein.

In one type of procedure in successful use it is customary to utilize both the bismuth phosphate treatment and the lanthanum fluoride treatment. Consequently, the bismuth phosphate treatment is referred to herein for background although the present invention is concerned particularly with the treatment of the fluoride type of carrier precipitate. That is, the present invention concerns the treatment of the fluoride type of precipitates, exemplified by lanthanum fluoride precipitates carrying Pu, or other fluoride materials such as potassium plutonium fluoride. In processes of the aforementioned type, either combination processes where several different types of carriers are used in which a fluoride carrier precipitation is accomplished in at least one of the steps, or processes wherein fluoride compounds are more or less directly precipitated, these fluoride precipitates carrying Pu or comprising a fluoride compound of Pu may present difficulties of redissolution. For example, these fluoride compounds may resist direct dissolution in acids. Consequently, prior to my invention a procedure termed "metathesis" was developed which included treating with alkali hydroxides, precipitates which presented difficulties of dissolution. This has been carried out by adding potassium hydroxide to the lanthanum fluoride carrying Pu in a suitable mixing vessel in order to perform an exchange reaction and convert the lanthanum compound to the hydroxide. The lanthanum hydroxide carrying Pu may then be dissolved in acids.

While the process of the prior art is in successful use, in some instances this standard metathesis has been found not to give as complete dissolution as desired and a residue remains in which Pu may be lost. Also in certain large scale operations materials such as grease may become incorporated in the process thereby presenting difficulties as respects dissolution of carrier precipitates.

In accordance with the present invention, there is provided an alternative method of dissolving fluoride types of compounds of or containing Pu, which process may be employed either in place of standard procedure under normal circumstances or where other types of procedures are not satisfactory or desired under the particular circumstances involved.

That is, by the present invention utilizing some of the same steps which have been previously worked out, but supplemented and altered in certain respects the advantage of improved reaction may be obtained as will be described.

The meaning of the terms bismuth phosphate type of process, wet fluoride type of process, product precipitate, and similar terms will be apparent as the description proceeds.

This invention has for one object, to provide improvements in methods for the separation and recovery of plutonium values.

Another object is to provide a method of separating plutonium values by a procedure characterized in that in certain steps different reagents and procedure than have heretofore been used are employed.

Still another object is to provide a procedure for dissolving fluoride compounds carrying or otherwise containing Pu values.

Still another object is to provide a procedure for dissolving fluoride carrier precipitates containing Pu values

which may more or less resist dissolution by usual dissolution methods.

Still further object is to provide a process for the dissolution of fluoride materials which may be used in place of or in conjunction with usual dissolution processes.

Still another object is to provide certain new and improved operations which lend themselves to the use of and to coupling with steps already known or practiced for the separation and recovery of a Pu value.

Another object is to provide a type of process which may employ some of the materials used in existing processes and which may be carried out in existing equipment without change, or with a minimum of equipment change.

Still another object is to provide a process for the recovery of Pu values which may be applied to fluoride precipitates containing Pu values either in relative small or large amounts.

Still another object is to provide a method of ultimately obtaining an acid solution of certain fluoride materials that resist direct dissolution in acid.

Other objects will appear hereinafter.

For a further understanding of the invention, reference will be made to the attached drawings forming a part of the present application. In these drawings, diagrammatic representations of embodiments of the invention are given in the form of flow sheets. Fig. 1 is a flow sheet for illustrating the coupling of the procedure of my invention with certain other steps. Fig. 2 is a flow sheet showing in greater detail an embodiment of the steps pertaining particularly to my invention.

It has been found that Pu in admixture with various extraneous material may be separated and concentrated by the use of the series of steps involving the utilization of a fluoride carrier precipitate type of treatment. These treatments are in accordance with known practice. However, I have found that the further processing of such carrier precipitates may be rendered simpler and more efficient by interposing the improvement features described herein such as the use of a different type of dissolution procedure and other variations. By the utilization of these features, not only are the advantages previously obtained in the processes still obtainable, but advantages are obtained such as the dissolution of fluoride precipitate and Pu away from certain residues and the easier removal of fluoride ions from the resultant hydroxide precipitates.

The types of carrier precipitates involved are described in application Ser. No. 519,714, filed January 26, 1944, Thompson and Seaborg, aforementioned and reference is made to that application for further disclosure, details thereof being omitted from the present disclosure except where necessary to an understanding of the present invention. As set forth in said application, it has been discovered that plutonium has more than one oxidation state, including a lower oxidation state or states herein referred to as Pu^(r) in which the element is characterized by forming insoluble phosphates and fluorides and a higher oxidation state or states referred to as Pu^(o) in which the element forms soluble phosphates and fluorides.

The aforementioned type of processes, namely the bismuth phosphate procedure and the fluoride procedure, are conducted under acid conditions. It has heretofore been customary to dissolve the fluoride carrier precipitate by potassium hydroxide metathesis as already mentioned and acidification of the resultant hydroxide slurry. However, it has been found in some instances that this standard metathesis may not give complete dissolution or otherwise involve certain problems.

I have found that an alternative method of dissolution of fluoride materials of the class indicated may be accomplished by using a carbonate type of solvent as described in detail herein. Not only is the dissolution facilitated under certain different situations such as in the presence of grease or upon residue resisting dissolution

by standard methods, but the method of dissolution may be carried out in place of the standard procedure if desired.

A general understanding of the application of my process in the field of separation and recovery of Pu values may be had by reference to the attached flow sheet, Fig. 1. In this figure the source of materials containing Pu values is indicated at 1. This source is exemplified by a nitric acid solution of uranyl nitrate, which 10 has resulted from or has been subjected to preliminary treatments exemplified by extraction and decontamination by the bismuth phosphate method. The solution may be oxidized at 2 and subjected to a standard fluoride by-product precipitation step for eliminating fission products and other undesired components. The oxidized 15 solution from 2 containing Pu^(o) is reduced at 3 in any conventional manner, and under the reduced conditions a lanthanum fluoride product precipitation applied at 4.

Referring now to the portion of the overall process to 20 which my invention is particularly directed, this lanthanum fluoride precipitate containing Pu values (product precipitate) after being separated in a conventional manner such as by centrifuging is then treated with a potassium carbonate type solvent of the present invention at 5. It has been found that, depending upon the character of this precipitate and similar factors, a large portion if not all of the precipitate readily dissolves and may be withdrawn to point 6.

The carbonate solution is treated at 7 with a source of 25 hydroxide ions for precipitating lanthanum hydroxide at 8. This lanthanum hydroxide carries the Pu and is in a form which may be readily dissolved in acid, such as nitric acid, as indicated at 9. The lanthanum nitrate formed at 10 may be withdrawn to 11 for further treatment as desired.

Any insoluble residues from step 10 may be withdrawn to point 12 and further treated with other solvents or the like at 13 to form further solution 14 which may be recycled to step 10 or otherwise used. Any residues at 40 15 from step 14 at this point in the process may be considered to have been exhausted of their Pu content and may be discarded.

Referring further to 5, as indicated, dependent upon the particular fluoride material treated, the bulk thereof 45 if not all, is dissolved and may be processed through the cycle just described. However, any undissolved lanthanum fluoride precipitate such as the material in the event the original precipitate is contaminated with grease or other additions, is conducted to treatment at 16. Further carbonate dissolution additions are applied at 17. The resultant carbonate solution may be combined with the solution at 6, or the resultant carbonate solution may be conducted to 18 where it is treated at 19 with KOH in a manner comparable to operation 7. The resultant 50 lanthanum hydroxide may be combined with the precipitate in operation 8.

The materials still undissolved from 17, usually relatively small at this point, may be withdrawn to 20, subjected to a special cycle of dissolution as indicated at 21, 60 22, 23, 24, and 25 inclusive and fed back into the process or otherwise used. However, at this point in the cycle, any Pu remaining is substantially negligible and this auxiliary recovery is optional.

Reference is now made to Fig. 2 which shows in detail 65 how the operation of my invention as designated under 5 of Fig. 1 may be broken down into a series of steps. That is, in the preferred and large scale operation my invention respecting the use of a carbonate solvent for dissolving fluoride materials would preferably be accomplished by using several different concentrations of carbonate solutions, several different steps of making the additions, several different steps in carrying out washings, and transfers from the centrifuge and other similar steps. That is, referring to Fig. 2 the first phase of the 70 operation under A comprises adding at least two additions

tions of carbonate solutions to the fluoride precipitate. As indicated on Fig. 2, this step may be carried out in a centrifuge, agitation accompanying the carbonate additions.

The residue from the primary carbonate addition as indicated at B may then be treated with further additions of a weaker carbonate solution. This residue remains in the centrifuge bowl, the dissolved portion having been conducted to the precipitation step designated C. The solutions resulting from B are conducted to C as may be the first washings from the centrifuge bowl. However, the later washings and residues from the centrifuge bowl may be discharged to waste or recovery treatments already referred to.

In step C the addition of a source of hydroxide ion is accomplished corresponding to operation 7 of Fig. 1. This operation is carried out in a standard reaction vessel such as a precipitator with an agitator. The resultant mixture of lanthanum hydroxide precipitate and supernatant liquor is then returned to the first-mentioned centrifuge or other centrifuge where the lanthanum hydroxide precipitate carrying Pu separates out in the centrifuge bowl. This lanthanum hydroxide precipitate is subjected to a series of washes with dilute alkali hydroxide solution and water as indicated under D of Fig. 2. The final washed lanthanum hydroxide precipitate is collected at E and may then be further processed in accordance with operation in 9, 10, and 11 referred to under Fig. 1 of the flow sheet.

The process of the present invention concerns particularly the dissolution of LaF_3 precipitate. The process may be employed in several ways, namely, to dissolve the entire LaF_3 precipitate, or the process may be used in conjunction with the standard metathesis procedure for treating any residue remaining from standard metathesis.

A still further understanding of my invention will be had by consideration of the following examples:

EXAMPLE I

A standard LaF_3 precipitate carrying Pu was treated with a 45% solution of K_2CO_3 . This solution was added in the proportion of about 30 cc. of the aforementioned 45% K_2CO_3 solution for each gram of lanthanum present. The reaction proceeds slowly at room temperature. Hence, it is preferred to carry out the treatment within the range of 50° C. to 95° C. for more rapid dissolution. The K_2CO_3 solution was added to the LaF_3 precipitate in several steps. That is, additional steps of K_2CO_3 treatment were made to that portion of the LaF_3 precipitate which had not gone into solution by the previous K_2CO_3 additions.

After the LaF_3 precipitate had been dissolved in the K_2CO_3 solution, the resultant solution was treated with KOH which precipitates $\text{La}(\text{OH})_3$ carrying Pu. The resultant $\text{La}(\text{OH})_3$ with Pu was then dissolved in nitric acid in accordance with standard procedure, and the resultant acid solution further treated in a usual manner for Pu concentration.

EXAMPLE II

Several runs have been carried out for applying the process of the present invention to relatively pure samples of LaF_3 . In the first of these 250 mg. of La (as LaF_3) containing 2.4 mg. of Pu were obtained from another concentration process. The LaF_3 was dissolved in 17 cc. of 45% K_2CO_3 which was added in two portions: 12 cc. and 5 cc. Each portion was heated for 30 minutes at 90° C. The undissolved residue after two K_2CO_3 treatments contained 0.9% of the Pu; the K_2CO_3 -KOH waste solution obtained after precipitating the $\text{La}(\text{OH})_3$ with KOH contained 0.1% of the Pu; and the very small residue which remained after dissolving the $\text{La}(\text{OH})_3$ in HNO_3 had no Pu. The Pu recovery in this case was 99%.

A second 250 mg. sample of La (as LaF_3) containing

75

14 mg. of Pu was obtained. The LaF_3 was dissolved by two additions of 45% K_2CO_3 using 6 cc. each time and heating for one hour at 50° C. The undissolved residue from these two K_2CO_3 treatments contained 0.05% of the Pu, while the waste K_2CO_3 -KOH solution contained 0.03% of the Pu. On dissolving the $\text{La}(\text{OH})_3$ with HNO_3 , there was no residue remaining. In this case the product recovery was 99.6%.

EXAMPLE III

A number of runs have been made with plant type LaF_3 precipitates. These samples had usually been through a BiPO_4 extraction and decontamination cycle before changing the carrier and the precipitation of LaF_3 .

In the first run, which was an extraction precipitate, the product in the final oxidized solution had been reduced with NaAsO_2 , then precipitated with 6.65 gm. of La. Considerable UF_4 was present in this LaF_3 precipitate. The LaF_3 was treated with 300 cc. of 45% K_2CO_3 at 90° C. for 1 hour. H_2O_2 was also added to oxidize the U^{+4} . The solution was then centrifuged and the residue treated again with 100 cc. of 45% K_2CO_3 at 90° C. for 1 hour; then centrifuged. 10 N KOH was added to each of these K_2CO_3 solutions to make them 2 N in KOH. The $\text{La}(\text{OH})_3$ precipitates were combined after washing once with 5 N KOH and twice with water. The waste K_2CO_3 -KOH solutions were separately analyzed. The $\text{La}(\text{OH})_3$ precipitate was dissolved in HNO_3 leaving a small residue. The material undissolved after two K_2CO_3 treatments was treated with 6 N HNO_3 giving a yellow solution and a black residue. The final results of this run are summarized below. No analysis was made of the starting material.

	Percent Pu
(1) Final $\text{La}(\text{NO}_3)_3$ product solution	93
(2) 1st K_2CO_3 -KOH waste solution	3.3
(3) 2nd K_2CO_3 -KOH waste solution	0.5
(4) 6 N HNO_3 solution of K_2CO_3 insoluble residue	3.3
(5) Residue insoluble in K_2CO_3 and HNO_3	0.5
(6) Residue remaining after dissolving $\text{La}(\text{OH})_3$ in HNO_3	0.0
	100

In this example 93% of the Pu was found in the product solution. Aside from the 3.3% diversion of Pu which was HNO_3 soluble and which could be recovered, the only other substantial diversion of Pu was that of 3.3% in the waste K_2CO_3 -KOH solution.

In the second run with plant LaF_3 the final oxidized solution was reduced with Fe^{+2} and H_2O_2 before precipitating with 6.65 gms. of La. In this run the solution of LaF_3 with K_2CO_3 was carried out at 50° C. The LaF_3 was treated with 330 cc. of 45% K_2CO_3 for 1 hour at 50° C. After centrifuging, the residue was treated with 165 cc. of 45% K_2CO_3 for 30 minutes at 50° C. The residue remaining was washed twice with 20% K_2CO_3 solution. The washings and the two K_2CO_3 solutions were combined. $\text{La}(\text{OH})_3$ was precipitated by making the solution 2 N in KOH. The $\text{La}(\text{OH})_3$ was washed once with 5 N KOH and twice with H_2O ; then dissolved with HNO_3 giving a clear solution plus a small residue. This solution is referred to below as 50° C. $\text{La}(\text{NO}_3)_3$ product solution.

The undissolved residue after the two K_2CO_3 treatments at 50° C. was heated with 50 cc. of 45% K_2CO_3 for 1 hour at 99° C. to determine whether any La still remained. $\text{La}(\text{OH})_3$ was precipitated as before (an amount $\frac{1}{10}$ to $\frac{1}{20}$ of that previously precipitated was found). This $\text{La}(\text{OH})_3$ was dissolved in HNO_3 giving a clear solution and a small residue. This solution is referred to below as 90° C. $\text{La}(\text{NO}_3)_3$ product solution.

The residue that was still insoluble in K_2CO_3 at 90° C. was treated with 6 N HNO_3 giving a light brown solution (Fe^{+3}) and a black residue. These were analyzed separately.

The results of this run are as follows. No analysis of the starting material was made.

	Percent Pu	5
(1) 50° C. $La(NO_3)_3$ product solution	91.0	
(2) Residue remaining after dissolving 50° C. $La(OH)_3$ in HNO_3	0.4	10
(3) 50° C. K_2CO_3 +KOH waste solution	3.5	
(4) 90° $La(NO_3)_3$ product solution	3.2	
(5) Residue remaining after dissolving 90° C. $La(OH)_3$	0.1	15
(6) 90° K_2CO_3 +KOH waste solution	0.05	
(7) 6 N HNO_3 solution of K_2CO_3 insoluble residue	1.5	
(8) Residue insoluble in K_2CO_3 and HNO_3	0.05	
	100	

The results of this run indicated that while two treatments with 45% of K_2CO_3 at 50° C. gave substantial recovery, in some instances a third step may be applied since an additional 3% of the Pu was recovered by the treatment at 90° C. In this run, however, during the K_2CO_3 extractions a bulky $Fe(OH)_3$ precipitate was present (Fe^{+2} had been used as the reducing agent). The waste K_2CO_3 +KOH supernatant contained 3.5% of the Pu. However, the total recovery of Pu was 94% and further recovery may be accomplished by ancillary steps.

As illustrated above a number of runs have been performed on the conversion of LaF_3 to $La(NO_3)_3$ by means of the K_2CO_3 procedure. Some of the runs were conducted with relatively pure LaF_3 prepared in the laboratory, and others with LaF_3 obtained from plant operations. The LaF_3 was usually treated with two portions of K_2CO_3 ; after treatment with the first portion, the residue was treated with a smaller portion. The undissolved residue was washed once or twice with a 20% K_2CO_3 solution, and the combined K_2CO_3 solutions and washes made 2 N in KOH to precipitate $La(OH)_3$. After washing once with KOH and twice with H_2O , the $La(OH)_3$ was dissolved in HNO_3 . A small residue may remain after dissolving the hydroxide in HNO_3 . In general the diversions of Pu were 1% or less when the procedure was applied to laboratory LaF_3 , but higher diversions were obtained with more impure LaF_3 from the plant. The highest diversion of Pu appeared to occur in the residue remaining after K_2CO_3 treatment and in the K_2CO_3 -KOH supernatant. In those cases in which an appreciable amount of Pu remains in the K_2CO_3 residue, it appears that a further K_2CO_3 extraction of the residue will remove the majority of the plutonium. The residue remaining after solution of the $La(OH)_3$ in HNO_3 contained only small amounts of Pu, if any. The plutonium that does remain is apparently not held by fluoride-insoluble material.

EXAMPLE IV

In order to recover Pu remaining in the K_2CO_3 -KOH waste solution when plant LaF_3 was treated, the following work was conducted. A standard KOH metathesis was performed on the plant LaF_3 , but an insoluble residue remained which contained about 85% of the Pu. A small aliquot of this residue was treated twice with 45% K_2CO_3 at 95° C., and $La(OH)_3$ precipitated by making the K_2CO_3 solution 2 N in KOH. About 99% of the product was found in the HNO_3 solution of $La(OH)_3$, and 0.4% in the K_2CO_3 -KOH waste solution. La^{+3} was added to the latter solution in several different ways in order to recover the product remaining in it. Conditions for the La^{+3} addition and the results obtained are summarized in the table.

Table.—Recovery of Pu from K_2CO_3 -KOH Supernatant by addition of La^{+3}

La^{+3} added mg./cc. in each addition	Number of Additions	Total La mg./cc.	Percent Pu Carried
0.1	1	0.1	65
0.1	2	0.2	95
0.1	3	0.3	95
0.3	1	0.3	80
1.0	1	1.0	80

The above procedure is essentially carrying of Pu by a "preformed" $La(OH)_3$ precipitate, and better recovery was obtained when the La^{+3} was added in several separate additions. The results indicate that about 95% of the Pu which may remain in the K_2CO_3 -KOH waste solution may be recovered by addition of two 0.1 mg./cc. portions of La^{+3} .

EXAMPLE V

In view of the fact that work indicated that two K_2CO_3 treatments would in general be adequate for dissolving LaF_3 , check runs were conducted to determine whether two treatments at 60° C. for 1/2 hour each would usually be satisfactory.

A portion of plant LaF_3 containing large amounts of Bi was washed twice with 2 N HCl to remove Bi therefrom. This reduced the amount of solid material by about one-half. The solid material remaining was treated with K_2CO_3 in a manner similar to that already described. About 81.2% of the Pu was found in the first K_2CO_3 solution, 17.0% in the second K_2CO_3 solution, and 2% in the K_2CO_3 washes; the Pu was therefore quantitatively extracted in this run. The K_2CO_3 -insoluble residue contained only 0.4% of the product. Despite the HCl wash used in this example, considerable Bi was still present, but the K_2CO_3 extraction was successful despite its presence. These results indicate that two K_2CO_3 treatment at 60° C. for 1/2 hour each are generally adequate to give good Pu recovery.

EXAMPLE VI

In accordance with this example the process was carried out in conjunction with conventional metathesis treatment. An attempt was made to metathesize a batch of LaF_3 of plant type with KOH, but on acidification of the precipitate following metathesis an insoluble residue containing 88% of the Pu remained. An attempt was made to retract the product from a small portion of this residue by treatment with concentrated HCl, but a maximum of only 68% was removed. Another small aliquot of the residue was treated with 2 portions of 45% K_2CO_3 at 95° C., and $La(OH)_3$ precipitated by making the combined K_2CO_3 solutions 2 N in KOH. The HNO_3 solution of the $La(OH)_3$ contained 99.6% of the Pu.

EXAMPLE VII

In accordance with this example batches of LaF_3 of plant type were routinely processed by the K_2CO_3 method with satisfactory results, in instances where KOH metathesis appeared inadequate. No trouble was encountered in the K_2CO_3 method due to grease or oil. It appears that the first plant batches had picked up a certain amount of grease. The largest diversion of Pu encountered in the procedure was the 1-2% Pu remaining in the K_2CO_3 -KOH supernatants. The amount of Pu found in other waste fractions was very small. Two 45% K_2CO_3 treatments (30 cc. each/g. La) at 95° C. for 45 minutes each were used. The residue was washed twice with 20% K_2CO_3 (10 cc. each/g. La) at 95° C. for 30 minutes. The K_2CO_3 solution was made 2 N in KOH to precipitate $La(OH)_3$ which was washed once with 2 N KOH and twice with H_2O prior to dissolving in HNO_3 . The 1-2% of product remaining in the K_2CO_3 -KOH supernatants was recovered by acidification to remove the carbonate,

making the solution 2 N in KOH and adding La^{+3} to precipitate $\text{La}(\text{OH})_3$ carrying Pu.

The diversion of Pu in the K_2CO_3 —KOH supernatant is probably a simple solubility effect since in some runs where the amount of plutonium has been greater the percentage diversion in this waste solution has only been of the order of 0.3%.

EXAMPLE VIII

In accordance with this example, the materials treated were similar to the plant materials described under Example V. However, in this particular instance, the materials contained a substantial amount of iron presumably dissolved from the stainless steel equipment used in carrying out prior treatment of the materials. The LaF_3 precipitate containing iron was treated in standard manner as above described with several potassium carbonate additions. However, in the first carbonate addition there was included a content of ammonium sulfide in an amount to provide a concentration of approximately 0.05 M—1 M thereof. A precipitate of iron sulfide formed which separated without loss of Pu thereby reducing the content of iron to a non-interfering amount. The Pu and other components dissolved in the carbonate solution in a manner the same as in the preceding examples. The treatment with potassium hydroxide and other regular processing was carried out.

By elimination of the iron the Pu subsequently isolated is more suitable for forming the peroxide derivative and for other similar purposes where a content of iron might promote decomposition.

EXAMPLE IX

In accordance with this example other materials containing a content of iron in the amount of 2.3×10^{-3} M was treated. The materials otherwise contained usual amounts of lanthanum and other components.

Treatments with 45% potassium carbonate were applied and wash treatments with 20% potassium carbonate as already described were also applied. However, the first carbonate addition contained about 0.05 M ammonium sulfide. The iron content was reduced to about 1.2×10^{-4} M namely by a factor of about 20.

From the foregoing therefore it is apparent that the K_2CO_3 -solution metathesis has proved to be a very satisfactory method for treatment of fluoride type precipitates. The K_2CO_3 method of the present invention is particularly useful in situations involving difficulties due to the presence of grease and other impurities.

The process may be applied to materials containing small amounts of Pu, such as tracer amounts or to materials containing relatively large amounts such as present in plant materials. The exact amount of Pu present is not a limitation on my invention. The quantities and concentration of reagents used are not a limitation upon the invention but are set forth herein as a guide to preferred operation. In general, in processes of the type described, in order to obtain favorable volume reductions and concentration, it is usually desirable to keep the quantities to a minimum consistent with good operation. However, this does not preclude the use of excess amounts of reagent if this should be desired.

Although the preferred solvent reagent comprises potassium carbonate, the reagent may be modified. For example, cesium and rubidium carbonates may be used. That is, it is believed that it is a concentrated source of carbonate ions that can be heated which provides the desired solution action. Hence, certain modifications of the solvent which do not alter this action may be made. The alkali hydroxides or similar alkali reagents may be employed in conjunction with the carbonate. The term carbonate solvent used herein is intended to embrace such a variety of solvents. While the use of potassium hydroxide has been described in the examples as the preferred reagent for supplying the source of hydroxyl ions

to obtain a lanthanum hydroxide precipitate, other sources of hydroxyl ions may be utilized. Sodium hydroxide is exemplary of such other reagents. In place of the use of lanthanum ion added for the recovery of Pu from the waste hydroxy-carbonate solution, other additions which cause the formation of an insoluble hydroxide may be used. For example, primary mention may be made of utilizing a source of bismuth ions in place of the lanthanum ions. Other metallic ions which may be used are exemplified by thorium, uranium, zirconium, and strontium.

As indicated, the process may be carried out in standard equipment. The fluoride materials containing Pu to be dissolved may be collected in a conventional solid bowl centrifuge and there treated with the carbonate solvent. The solution resulting may be centrifuged out and conducted to other conventional equipment for further treatment. It will be observed that in many instances at least 90% dissolution is accomplished in the first treatment with the carbonate solvent. By the application of the other auxiliary steps described, substantially complete recovery may be obtained.

Although the process has been described in connection with the treatment of a fluoride material carrying or containing Pu, exemplified by lanthanum fluoride treated in a centrifuge, as this represents conditions frequently encountered in plant operations, my invention is not limited in these respects. For example, other materials such as plutonium fluoride, potassium plutonium fluoride, potassium lanthanum fluoride and the like may be treated by my invention. Likewise, rather than carrying out the dissolution in a centrifuge, the process may be carried out in tanks in a manner analogous to tank metathesis used industrially. Or other apparatus may be used.

According to the best evidence available, the oxidation state of plutonium secured in solution by the action of the oxidizing agents referred to herein and in cited co-pending application Serial No. 519,714, now U.S. Patent No. 2,785,951, is greater than four, the oxidation state secured in solution by the action of the reducing agents referred to herein and therein is no greater than four. It should therefore be understood that, as used herein, "Pu^(o)" and "Pu in the (o) condition (or state)" are both synonymous with "plutonium in an oxidation state greater than four" and "Pu^(r)" and "Pu in the (r) condition (or state)" are both synonymous with "plutonium in an oxidation state no greater than four."

I claim:

1. In processes for plutonium recovery which comprise carrier precipitation of plutonium values from solution with a lanthanum fluoride carrier precipitate, and subsequent derivation from the resulting plutonium-bearing carrier precipitate of an aqueous acidic plutonium-containing solution, the improvement method in said derivation which comprises contacting said carrier precipitate with a concentrated aqueous solution of potassium carbonate to effect dissolution therein of at least a part of said precipitate, including said plutonium values, separating the resulting solution from any remaining precipitate and contacting said remaining precipitate with an aqueous solution containing at least 20 percent by weight of potassium carbonate to effect dissolution therein of said remaining precipitate, and thereupon combining the resulting solutions and incorporating therein an alkali metal hydroxide to a concentration of at least approximately 2 normal to precipitate lanthanum ions consequently contained therein, as lanthanum hydroxide, and concomitantly carrier precipitate therewith said plutonium values therefrom.
2. In processes for plutonium recovery which comprise carrier precipitation of plutonium values from solution with a lanthanum fluoride carrier precipitate, and subsequent derivation from the resulting plutonium-bearing carrier precipitate of an aqueous acidic plutonium-containing solution, the improvement method in said der-

ivation which comprises contacting said carrier precipitate with an aqueous potassium carbonate solution of substantially 45% by weight concentration to effect dissolution therein of at least a part of said precipitate, including said plutonium values, separating the resulting solution from any remaining precipitate and contacting said remaining precipitate with an aqueous potassium carbonate solution of substantially 20% by weight concentration to effect dissolution therein of said remaining precipitate, and thereupon combining the resulting solutions and incorporating therein potassium hydroxide to a concentration of approximately 2 normal to precipitate lanthanum ions consequently contained therein, as
